M. BLOOM

CASING FOR A DISPENSING CABINET

Filed Nov. 17, 1923

Marcus Bloom.

INVENTOR

BY Victor J. Evans

ATTORNEY

WITNESS:

UNITED STATES PATENT OFFICE.

MARCUS BLOOM, OF CHARLOTTE, NORTH CAROLINA.

DESIGN FOR A CASING FOR A DISPENSING CABINET.

Application filed November 17, 1923. Serial No. 7,797. Term of patent 14 years.

To all whom it may concern:

Be it known that I, MARCUS BLOOM, a citizen of the United States of America, residing at Charlotte, in the county of Mecklenburg and State of North Carolina, have invented a new, original, and ornamental Design for a Casing for a Dispensing Cabinet, of which the following is a specification, reference being had to the accompanying drawings, forming a part hereof.

The figure is a perspective view showing my new, original and ornamental design for a casing for a dispensing cabinet.

I claim:—

The ornamental design for a casing for a dispensing cabinet as shown.

MARCUS BLOOM.
